F. P. DOOLEY.

WIRE FABRIC.

APPLICATION FILED APR. 20, 1914.

1,106,551.

Patented Aug. 11, 1914.

Inventor:

Frank P. Dooley

By G. L. Gray

UNITED STATES PATENT OFFICE.

FRANK P. DOOLEY, OF CHICAGO, ILLINOIS.

WIRE FABRIC.

1,106,551.

Specification of Letters Patent. Patented Aug. 11, 1914.

Application filed April 20, 1914. Serial No. 833,202.

To all whom it may concern.

Be it known that I, FRANK P. DOOLEY, a citizen of the United States, residing at Chicago, in the county of Cook and State 5 of Illinois, have invented a certain new and useful Improvement in Wire Fabrics, of which the following is a full, clear, concise, and exact description, reference being had to the accompanying drawings, forming 10 a part of this specification.

My invention relates to those wire fabrics made up of a plurality of rows, disposed side by side, of fabric links and parallel stringers arranged transversely to the rows 15 of links for the purpose of assembling the rows. In structures of the prior art the links in each row have been directly interconnected and have had engagement with the cross stringers where interconnected.

20 In devices of my invention the cross stringers operate not only to join the adjacent rows of fabric links but also to have or carry portions which serve as minor links that join adjacent major links in each row.

25 These minor link portions are preferably constituted of looped continuations of the cross wire stringers with which adjacent ends of adjacent major links in the same rows are connected, the minor links being 30 engaged at their ends with adjacent ends of adjacent major links.

I will explain my invention more fully by reference to the accompanying drawing showing the preferred embodiment thereof 35 and in which—

Figure 1 is a plan view of a fabric element made in accordance with my invention; and Fig. 2 is a perspective view of a part of the structure illustrated in Fig. 1.

40 Like parts are indicated by similar characters of reference in both figures.

The wire fabric is desirably provided with a suitable form of rigid support which is illustrated in the drawing as a frame *a* 45 whose side and end portions are made of angle iron. The helical springs *b* are secured at their outer ends to end rails of the frame. The springs at the outer longitudinal borders of the structure are connected 50 with longitudinal stringers *c* which are shown in the drawing as being in the form of iron strips but to the employment of which stringers and the form thereof the invention is not to be limited since one ad- 55 vantage derived from the device of my invention resides in the fact that these side

stringers need not be relied upon to complete the fabric. The coil springs *b* intervening between those coil springs to which the stringers *c* are attached are connected 60 at their inner ends with the major fabric links *d* at the ends of the rows of fabric links. As the invention is illustrated each major fabric link *d* is formed of a piece of wire bent into closely approached branches 65 that converge toward the ends of the folded wire, the ends of each folded wire being underturned to form a hook structure *e*, each hook structure thus having two hooks included in its formation. The bights of the 70 links at one end of the fabric may lie in the same plane with the side branches of the links, these bights receiving the inner hook ends of their helical springs *b*. The hooks *e* in which the links at the top of the fabric 75 terminate receive the inner hook ends of their helical springs *b* at the other end of the fabric. The hooks *e* are downwardly projected and lie in planes transverse to the general plane of the fabric so that the 80 upper surface of the fabric may be free of projections that would injure a mattress or other object to be supported thereby. The adjacent longitudinal rows of fabric units *d* are spaced apart and held in proper relation 85 by cross wire stringers *f* which not only perform this function but also carry, each, a transverse row of minor links *g* which are included in each longitudinal row of links *d* and serve to unite adjacent ends of adjacent 90 links and space such adjacent links apart.

In the preferred embodiment of the invention the minor links *g* are integral parts of the stringers *f* and are formed by looping 95 the stringer *f* into the form of the minor links at intervals equaling the spacing that is to intervene between adjacent longitudinal rows of major links, the minor links lying in the general plane of the fabric. The base 100 portions of the minor links, that is those portions thereof which are immediately adjacent the straight portions of the stringers *f*, are, at each minor link, closely approached to constitute necks in the minor links. The 105 bulging portions of the minor links receive the hooks *e*. The necks of the minor links are received by bights of the major links. These bights in the major links which receive the neck portions of the minor links 110 are preferably downwardly turned to project transversely of the general plan of the fabric

so that the fabric, at its upper and object supporting surface, may be as flat as is practicable. It will be observed that the bights of those major links that receive the neck 5 portions of the minor links operate to prevent the sides of the minor links from spreading apart whereby the aggregate lengths of the transverse wire stringers *f* are substantially unchangeable whereby the 10 fabric will not permanently sag so far as the wire stringers *f* are concerned. In short, a fabric constructed in accordance with my invention is one which, when properly mounted, will substantially maintain its 15 shape.

While I have herein shown and particularly described the preferred embodiment of my invention I do not wish to be limited to the precise details of construction shown as 20 changes may readily be made without departing from the spirit of my invention; but

Having thus described my invention I claim as new and desire to secure by Letters Patent the following:

25 1. A wire fabric including a plurality of rows of major wire links; minor wire links uniting adjacent major links in each row of major links; and wire stringers extending across the fabric and uniting the adjacent 30 rows of major fabric units into a fabric, each stringer carrying a transverse row of minor links that are included in the rows of major links that are joined by such stringer, each stringer and the minor wire links carried 35 thereby being integrally formed of the same wire, the major links being in the form of bent wires whose bights engage the stringers at the base portions of the minor links, the ends of the major links opposite their bights 40 being formed into hooks which are received by minor links.

2. A wire fabric including a plurality of rows of major wire links; minor wire links uniting adjacent major links in each row of

major links; and wire stringers extending 45 across the fabric and uniting the adjacent rows of major fabric units into a fabric, each stringer carrying a transverse row of minor links that are included in the rows of major links that are joined by such stringer, 50 each stringer and the minor wire links carried thereby being integrally formed of the same wire, the major links being in the form of bent wires whose bights engage the stringers at the base portions of the minor links 55 which are contracted to form necks and which bights receive and engage such minor link necks, the ends of the major links opposite their bights being formed into hooks which are received by minor links. 60

3. A wire fabric including a plurality of rows of major wire links; minor wire links uniting adjacent major links in each row of major links; and wire stringers extending 65 across the fabric and uniting the adjacent rows of major fabric units into a fabric, each stringer carrying a transverse row of minor links that are included in the rows of major links that are joined by such stringer, 70 each stringer and the minor wire links carried thereby being integrally formed of the same wire, the major links being in the form of bent wires whose bights are turned to be angular to the general plane of the fabric and engage the stringers at the base portions 75 of the minor links which are contracted to form necks and which bights receive and engage such minor link necks, the ends of the major links opposite their bights being formed into hooks which are received by 80 minor links.

In witness whereof, I hereunto subscribe my name this twenty-fourth day of March A. D., 1914.

FRANK P. DOOLEY.
